Morris Paschman, New York, N. Y.

Application June 19, 1946, Serial No. 130,856

Term of patent 3½ years

(Cl. D45—19)

To all whom it may concern:

Be it known that I, Morris Paschman, a citizen of United States, residing at New York city, in the county of Kings and State of New York, have invented a new, original, and ornamental Design for a Pin or Similar Article, of which the following is a specification, reference being had to the accompanying drawing, forming part thereof.

In the drawing:

Fig. 1 is a front view of a pin showing my new design;

Fig. 2 is a rear view thereof; and

Fig. 3 is a cross-sectional view taken on line 3—3 of Fig. 2.

I claim:

The ornamental design for a pin or similar article, as shown.

MORRIS PASCHMAN.
